UNITED STATES PATENT OFFICE.

JOHN OTIS REMINGTON, OF HINGHAM, ASSIGNOR TO BURR, BROWN & CO.,
OF BOSTON, MASSACHUSETTS.

DESIGN FOR TRIMMING.

SPECIFICATION forming part of Design No. 13,544, dated January 23, 1883.

Application filed November 27, 1882. Term of patent 3½ years.

To all whom it may concern:

Be it known that I, JOHN OTIS REMINGTON, a citizen of the United States, residing at Hingham, in the county of Plymouth and State of Massachusetts, have invented certain new and useful Improvements in a Design for Trimmings; and I do hereby declare the following to be a full, clear, and exact description of the invention, such as will enable others skilled in the art to which it appertains to make and use the same, reference being had to the accompanying drawing, and to letters or figures of reference marked thereon, which form a part of this specification.

This design consists in two markedly distinct features—a flat band, which is the base or ground of the design, and a raised flat rib arranged centrally and longitudinally of such band, so as to stand out in bold relief from it.

The band is of galloon or other material, more

or less tasteful in appearance, while the central rib is of chenille or similar ornamental material.

The accompanying drawing represents an isometric view of a piece of trimming containing my design.

In this drawing, A represents the flat band or ground. B is the raised flat-surfaced rib, extending in bold relief from the band A.

I claim—

The design for trimming herein shown and described, the same consisting of the band or groundwork A and the rib B, extending in relief from such groundwork.

In testimony whereof I affix my signature in presence of two witnesses.

JOHN OTIS REMINGTON.

Witnesses:

H. E. LQDGGE,
F. CURTIS.
